UNITED STATES PATENT OFFICE.

PETER SJOSTROM, OF MAPLEWOOD, MASSACHUSETTS, ASSIGNOR TO VICTOR SHOE MACHINERY COMPANY, OF LYNN, MASSACHUSETTS, A CORPORATION OF MASSACHUSETTS.

STITCH-MEASURER FOR SEWING-MACHINES.

1,219,597.

Specification of Letters Patent. Patented Mar. 20, 1917.

Application filed December 13, 1915. Serial No. 67,060.

To all whom it may concern:

Be it known that I, PETER SJOSTROM, a subject of the King of Sweden, and a resident of Maplewood, in the county of Middlesex and State of Massachusetts, have invented certain new and useful Improvements in Stitch-Measurers for Sewing-Machines, of which the following is a specification.

This invention relates to devices for regulating the length of stitches in welt sewing machines, and has for its object the provision of means whereby the number of stitches to an inch may be predetermined, the present invention being an improvement upon the invention shown and described in another application of mine filed Feb. 17, 1915, and numbered 9,465.

The invention consists of a device coacting with the work feeding mechanism which may be set in such a manner as to limit the movements of said mechanism and thereby control the length of the stitches to be inserted in the work.

The invention further consists in certain novel features of construction and arrangement of parts which will be fully understood by reference to the description of the drawings and to the claims hereinafter given.

Of the drawings:

Fig. 1 represents an end elevation of a sewing machine embodying the principles of the present invention.

Fig. 2 represents a horizontal section on line 2—2 on Fig. 1.

Fig. 3 represents a vertical section on line 3—3 on Fig. 2.

Fig. 4 represents a vertical section on line 4—4 on Fig. 1, and

Fig. 5 represents a section of the scale and the movable arm coacting therewith.

Similar characters designate like parts throughout the several figures of the drawings.

In the drawings, 19 is a connector, the lower end of which is connected to any well-known form of driving mechanism, while the upper end is pivotally connected to a lever 20 loosely mounted upon a stud 21 non-revolubly mounted in a boss formed upon the frame 23, the base 24 of which is adapted to be secured to any well-known form of support.

The lever 20 is secured by means of the bolt 26 to the gear segment 27, the hub 28 of

which is mounted upon the stud 21 about the axis of which it is adapted to be oscillated. The hub 28 is preferably provided with a reduced cylindrical extension projecting through the hub of the lever 20 as shown in Fig. 1.

The teeth of the gear segment 27 mesh with the teeth of the gear 29 secured to a shaft 30 mounted in bearings in the frame 23, in which bearings said shaft is adapted to be oscillated by means of the gear segment 27.

During the oscillation of the gear segment 27 the lever 20 moves through an arc of a circle. The shaft 30 has loosely mounted thereon a disk member 31 having formed thereon radial shoulders 32—33 which are adapted to be engaged by a pin 34 extending laterally from the gear 29. This pin 34, during the oscillation of the gear 29, will impart movement to the disk 31 when contacting with either of the shoulders 32—33, while permitting said disk to remain at a standstill at the beginning of the movement of said pin 34 in either direction, that is, while traveling from the shoulder 32 to the shoulder 33 or vice versa.

The disk 31 is provided with a cam projection 35 adapted to engage the truck 36 on a lever 37 pivoted at 38 to the frame 23, the opposite end of said lever 37 being provided with a bearing member 39 adapted to engage the awl carrier 40 when it is desired to feed the work. The awl carrier 40 is provided with the usual curved awl 41. The truck 36 is retained normally in contact with the cam 35 by the spring 37* which forces the front end of the lever 37 outwardly, this outward movement being limited by the stop pin 38*.

The bearing member 39 consists of a screw threaded to the end of the lever 37 and held in adjusted position by means of the clamping nut 42. The awl carrier 40 is mounted upon a pin 43 extending through a boss 44 formed upon the side of the needle carrier 45, said pin being prevented from rotating by means of the clamping screw 46. The needle carrier 45 is provided with the usual curved barbed needle 47 and oscillates about the stud 47* fixed in the frame 23.

The needle carrier 45 is provided in its outer face with a depression in which is mounted a spring 48 normally tending to force the awl carrier 40 outwardly away

from the needle carrier 45, said outward movement being limited by the stop member 49 mounted in the tubular member 50 secured to the frame 23.

5 The tubular member 50 has a diametral slot 51 at one end in which the blade of a screw driver is adapted to be positioned to prevent the turning of said member 50 when the clamping nut 52 is being screwed thereon.

10 Between the nut 52 and the boss 53 projecting from the frame 23 is positioned a curved plate 54, said plate being adapted to be clamped in position by the nut 52.

If it is desired to adjust the position of 15 this plate 54 about the axis of the member 50 the nut 52 is moved outwardly sufficiently to permit such adjustment and the plate 54 is then again clamped.

The stop member 49 is threaded to the 20 tubular member 50 and when rotated is moved endwise thereof so that its inner end will control the outward movement of the awl carrier 40.

The rotation of the member 49 is effected 25 by means of the arm 55 clamped to the outer end of the member 49 by means of the clamping nut 56 threaded to the reduced end 57 of said member.

The movement of the arm 55 in opposite 30 directions is limited by the ears 58-59 projecting outwardly from the scale plate 54.

The plate 54 is provided with a plurality of indentations 60 with a numeral 61 opposite each indentation. The arm 55 is provided with a projection 62 adapted to engage with either of the indentations 60 to lock the arm 55 in adjusted position.

Each numeral 61 indicates the number of 35 stitches that will be formed in the work to every inch when the arm 55 is registering with an indentation 60 opposite said numeral.

It is obvious that the more stitches that 40 are formed to an inch the shorter these stitches will be, and vice versa.

The length of the stitches is regulated by 45 the movement of the awl carrier 40, and it is self-evident that this movement is controlled by the position of the inner end of the member 49, which position may be varied at will by the arm 55.

In the operation of the machine the oscillation of the segment 27 will impart oscillatory movement to the gear 29, and through 50 this gear 29 to the main driving shaft 30. The pin 34 on the gear 29 will coact with the shoulders 32 and 33 of the cam member 35 and move this cam member 35 at the end of the movement of the pin 34 in either direction. The movement of the cam 35 will operate the lever 37 moving it about its pivot 38 and cause the bearing member 39 to force the awl carrier 40 toward the needle carrier 45, the awl 41 at this time being in the work 55 and causing the work to be fed so that the

puncture therein caused by the awl will be brought into the plane of the needle 47, the awl 41 on completing its reverse movement being returned to its normal position by means of the spring 48. This reverse movement of the awl carrier does not occur until the point of the awl is entirely free from the under face of the work. Any required feed may be obtained by adjusting the feed controlling member 49.

70 The machine is provided with the usual work support 118, the shuttle 145 and all the necessary instrumentalities for the formation of the stitch, but as these devices form no part of the present invention they are not 80 herein described.

75 It is believed that the operation and many advantages of this machine will be fully understood from the foregoing description.

Having thus described my invention, I 85 claim:

1. In a machine of the class described, the combination of an oscillating member; a work feeding member vertically mounted thereon; a stop member to limit the outward movement of said work feeding member about its pivot; and means for adjusting said stop member endwise a predetermined amount.

2. In a machine of the class described, the 95 combination of a vertically oscillating awl carrier having also a lateral swinging movement; a stop member to limit the outward swinging movement of said awl carrier; and means for adjusting said stop member endwise a predetermined amount.

3. In a machine of the class described, the combination of an oscillating awl carrier; a support; a stop member threaded to said support; and means for rotating said stop 105 member and effecting endwise movement thereof.

4. In a machine of the class described, the combination of an oscillating awl carrier; a support; a stop member threaded to said 110 support; a curved plate provided with a plurality of registering members; and an arm secured to and rotatable with said stop member and adapted to coact with either of said registering devices.

115 5. In a machine of the class described, the combination of an oscillating awl carrier; a support; a stop member threaded to said support; a curved plate provided with a plurality of indentations; and an arm secured 120 to and rotatable with said stop member and provided with a projection adapted to coact with either of said indentations.

6. In a machine of the class described, the combination of an oscillating awl carrier; a 125 support; a stop member threaded to said support; a curved plate provided with a plurality of registering members and having an outwardly extending arm-engaging ear at each end; and an arm secured to and ro- 130

tatable with said stop member and adapted to coact with either of said registering devices.

7. In a machine of the class described, the combination of an oscillating awl carrier; a fixed tubular member; a stop member threaded therein; and means for rotating said stop member and effecting endwise movement thereof.

10 8. In a machine of the class described, the combination of an oscillating awl carrier; a fixed tubular member; a stop member

threaded therein; a curved scale plate clamped on said tubular member; and means coacting with said plate for rotating said 15 stop member and effecting endwise movement thereof.

Signed by me at Lynn, Mass., this 19th day of October, 1915.

PETER SJOSTROM.
